UNITED STATES PATENT OFFICE.

CHARLES SPIRO, OF NEW YORK, N. Y.

TYPE-BAR MOVEMENT.

No. 918,790.

Specification of Letters Patent. Patented April 20, 1908.

Application filed December 27, 1907. Serial No. 408,237.

To all whom it may concern:

Be it known that I, CHARLES SPIRO, a citizen of the United States, residing at New York, county of New York, and State of New York, have invented certain new and useful Improvements in Type-Bar Movements, of which the following is a specification, reference being had therein to the accompanying drawing.

10 This invention relates to a type bar movement, and particularly to a key lever and lever co-operatively connected to actuate the type bar.

The invention has for an object to provide 15 a novel and improved construction of key lever having an angular extension therefrom by which it is pivoted, and a rocker face in contact with a co-operating lever connected with a type bar.

20 A further object of the invention is to provide a guiding and supporting plate having a slot in which both the key lever and type lever are mounted so that they are constantly retained in parallelism during their 25 travel to secure an easy and accurate movement of the parts.

Another object of the invention is to provide upon the angular extension of the key lever a curved rocker face which bears 30 against the type lever above the pivot thereof so that in the depression of the key lever this face engages the type lever first at the highest point above its pivot, and in the rocking movement the point of contact descends until the lower portion of the extension is 35 reached when the type is in contact with the platen. This secures the desired leverage to overcome the inertia of the type bar when at rest and to continue an even upward movement thereof requiring the minimum power and also the minimum extent of travel of the 40 key lever for that purpose.

Other and further objects and advantages 45 of the invention will be hereinafter set forth and the novel features thereof defined by the appended claims.

In the drawing:—Figure 1 is a perspective of the invention, the supporting parts being shown in section; Fig. 2 is a side elevation 50 thereof with the type bar at rest; Fig. 3 is a similar view with the type bar in contact with the platen; and Fig. 4 is a detail perspective of the supporting and guiding plate with the key and type levers indicated in dotted lines.

55 Like numerals refer to like parts in the several views of the drawing.

The numeral 10 designates the key lever which may be of any desired construction or configuration and is provided at its front portion with the usual key 11 and extends through a slot in the guide plate 12 carried by the frame of the machine in the ordinary manner. The rear of this key lever is provided with an angularly disposed extension 13 which in the present illustration is at substantially a right angle to the body of the lever, and is provided at its upper end with a pivotal connection, the same being here shown in the form of a hook 14 adapted to engage the supporting flange 16 of the supporting and guiding plate 15 shown in Fig. 4. The outer face of this extension is curved as at 17 upon a suitable arc to provide a rocking motion thereof in the oscillation of the lever upon its pivot. In order to retain this lever 75 in contact with the flange 16 a suitable guard piece 18 is disposed above the same. This form of key lever is adapted to actuate and control any desired mechanism brought into contact therewith, and in its application to 80 a typewriter the rocker face 17 is disposed in contact with the type lever 19 which is slotted at its lower end 20 and mounted upon an angle plate 21 carried by the frame of the machine and extending across the same to 85 accommodate a series of levers. The lever is located in the slot 22 of the supporting and guide plate 15 and both the key and type levers being of plate material are disposed in the same slot to travel therein at all times 90 and are thus firmly held in alignment. The lever is normally drawn toward the front of the machine by means of the tension spring 23 extending therefrom to the flange plate 21. The upper end 24 of the type lever is 95 connected by a ligament 25 with the type bar 26. This bar may be of any desired character and is here shown mounted upon a supporting plate or sector 27 and provided with the connecting plate 28 for the ligament. 100 When at rest the bar is disposed upon the usual support 29 and in its upward travel engages the front face of the plate 30 also mounted to travel in the usual manner. The key and type levers are duplicated to correspond with the type bars or other parts to be actuated and are all supported by the common plates extending across the machine frame, only one set of said bars being here illustrated.

110 In the operation of the invention the position of the parts when at rest is shown in

Fig. 2, while a depression of the outer end of the key lever causes the lower portion of the angular extension thereon to advance toward the type lever and having the rocking 5 face secures a smooth and easy action with the leverage starting at a point removed from the pivot of the type lever and advancing toward said pivot at the close of the action at which time the type bar is in contact 10 with the platen, as shown in Fig. 3. The construction of the key lever having a pivot at the upper portion of its extension provides for the maximum leverage between the parts with a minimum travel at the key 15 end of the lever thus producing the smooth and easy action with a short stroke most desirable in typewriting machines and other mechanism actuated from key levers. The coöperation of the type lever with this extension of the key lever provides a convenient structure for conveying the oscillatory motion of the key lever to the type bar in rising from its point of rest into contact with the platen. The supporting and guard plate 20 having the series of slots to accommodate the successive sets of key and type levers provides for the proper hanging of the key levers and the supporting and guiding of the type levers in direct contact therewith by 25 which their alinement and accurate operation is assured. When the key levers are hung upon the supporting flange they may be all secured in position by the locking piece extending above the top thereof at a 30 distance sufficient to permit the rocking action of the bars upon their support while the angle plate of the machine forms a positive pivotal support for the slotted lower ends of the type levers. It will thus be seen 35 that the invention presents a type bar movement adapted to be formed of sheet material by a stamping or pressing operation and one which is both efficient in operation and economical in construction.

45 Having described my invention and set forth its merits, what I claim and desire to secure by Letters Patent is:—

1. In a type bar movement, a key lever having an angular extension provided with 50 a laterally disposed hook at the upper end thereof from which the lever is suspended and a rocker face at the edge of said extension opposite said hook.

2. In a type bar movement, a key lever 55 having an angular extension provided with a pivoting hook at the upper end thereof, a fixed supporting flange for said hook having at its lower portion a guide slot for said key lever extension, and a type lever engaging 60 said key lever and disposed in said slot.

3. In a type bar movement, a key lever having an angular extension provided with a pivoting hook at the upper end thereof, a fixed supporting flange for said hook, and a

retaining device disposed above said hook 65 and flange.

4. In a type bar movement, a key lever having an angular extension provided with a pivoted hook at its upper end, a fixed supporting flange for said hook having at its 70 lower portion a guide slot for said key lever, a type lever engaging said key lever and disposed in said slot, and a tension spring from said type lever to a fixed part disposed to retain the type lever in contact with the key 75 lever.

5. In a type bar movement, a key lever, a coöoperating type lever, and a slotted guide adapted to receive each of said levers and provided with a pivoting edge for the key 80 lever at one end of said slots.

6. In a type bar movement, a key lever, a type lever and a slotted guide provided at one side with a vertically disposed supporting flange and at the opposite side with a de- 85 pending slotted guide flange.

7. In a type bar movement, a slotted guide provided at one side with a vertically disposed supporting flange and at the opposite side with a depending guide flange, a key 90 lever mounted upon said supporting flange, a type lever disposed within the guiding slot of the depending flange, and an angular bar upon which said key lever is pivotally mounted in alinement with said depending flange. 95

8. In a type bar movement, a slotted guide provided at one side with a vertically disposed supporting flange and at its opposite side with a depending guide flange, a key 100 lever mounted upon said supporting flange, a type lever disposed within the guiding slot of the depending flange, an angular bar upon which said key lever is pivotally mounted in alinement with said depending flange, and 105 a coil spring extending from said key lever to said angle bar.

9. In a type bar movement, a key lever provided at its inner end with an angular extension having a curved rocker face, a type bar 110 connected to the upper end of said type lever, and a plate having a pivot for said extension and a guide for said type lever. 115

10. In a type bar movement, a key lever provided at its inner end with a vertical extension, a type lever in contact with said extension and provided with a pivot slot at its lower end, an angle bar disposed in said slot, 120 a pivoted type bar, and a ligament from said type bar to the upper end of the type lever.

In testimony whereof I affix my signature in presence of two witnesses.
